JAMES SHEPARD.

UNITED STATES PATENT OFFICE.

JOSEPH OTTNER, OF NEW BRITAIN, ASSIGNOR TO HART MANUFACTURING COMPANY, OF KENSINGTON, CONNECTICUT.

DESIGN FOR A PAPER-CLIP.

Specification forming part of Design No. 5,694, dated March 19, 1872.

To all whom it may concern:

Be it known that I, JOSEPH OTTNER, of New Britain, in the county of Hartford and State of Connecticut, have invented and produced a new and original Design for a Paper-Clip, of which the following is a specification:

The nature of my design is fully represented by the accompanying engraving, to which reference is made.

A represents the clip proper, and B its base. The contour of these parts is composed of straight and curved lines, so joined as to form the various curves and corners, as shown. The

part A is bordered by a raised ledge, the space inclosed thereby being filled with raised ornamental work of the design shown. The base B is also bordered by a raised ledge, which is narrower than the ledge which borders A, and the surface of B inside the ledge is checked or roughened.

I claim as my invention—

The design for a paper-clip, as shown.
JOS. OTTNER.

Witnesses:

F. H. CHURCHILL,
JAMES SHEPARD.
